UNITED STATES PATENT OFFICE.

WILLIAM MILTON BROWN, OF JOHNSTOWN, PENNSYLVANIA.

RAILWAY-SWITCH.

SPECIFICATION forming part of Letters Patent No. 554,437, dated February 11, 1896.

Application filed November 14, 1894. Serial No. 528,716. (No model.)

To all whom it may concern:

Be it known that I, WILLIAM MILTON BROWN, of Johnstown, county of Cambria, State of Pennsylvania, have invented a new and useful Improvement in Railway-Switches, of which the following specification is a true and exact description, due reference being had to the accompanying drawings.

My invention (Case No. 54) relates to an improved form of switch for use in the track of street-railways, and has for its object to provide a switch that may be thrown by the operator of the car without leaving the car-platform.

My switch being operated by electricity, it is especially adapted to use in an electric road, and I will so describe it.

Referring to the drawings, Figure 1 represents a top view of a portion of track containing a switch embodying my invention. Fig. 2 is a cross-section of the street through the switch. Fig. 3 illustrates certain electrical details hereinafter described. Fig. 4 represents a top view of one of the switch-boxes. Fig. 5 represents a section on line X X of Fig. 4.

In general my invention consists in operating the switch by a suitable electric motor, placing in the track switches adapted to so admit the current into the motor that it will operate the switch in either direction, and closing the electrical switch by means of suitable magnets suspended from the car.

In the drawings, A is the switch to be operated by the motor B through the chain connections, as shown. Between the track-rails are placed the boxes C' C². These boxes contain the switches which admit the current to the motor, the wires being connected from the switch-boxes to the motor in suitable pipes T.

Suspended from the car in Fig. 2 are two electromagnets D' and D², so located that they pass directly over the boxes C' and C².

E is the trolley-wire and e the trolley contact-wheel.

F' and F² are two switches, adapted to be operated by the motorman and by which he may pass a current of electricity from the trolley through either magnet desired, thereby rendering it active.

Inside the boxes C' and C² are the switches shown in Fig. 3, 4, and 5. They consist of the

cranks H' and H², pivoted on pins h. These pivot-pins are insulated from the remainder of the crank by the insulation I. The vertical arm of the crank is divided into two parts insulated from each other, as shown. These two parts are so arranged that by the upward movement of the horizontal arm of the crank, which arm carries the long iron bars R' or R², they make contact with four contact-points K' L' M' N' or K² L² M² N², as the case may be. These several contact-points are connected with the motor B by the wires k, l, and m, as follows: O' and O² are the coils of the field-magnets of the motor B, and P is the commutator with which the brushes p' and p² make contact. The trolley-wire is connected by the wire e' to the field-coil O', the circuit passing from it to the other field-coil O² in the usual manner. The wire k connects this last coil O² with the contact-points K' and K². The wire l connects brush p' with contacts L' and L², and the wire m connects the brush p² with contacts M' and M². The other contacts N' and N² are connected with the grounds G by wires n.

I will now describe the operation of the switch. Let us suppose a car be approaching the switch from the left hand, so that it will pass over the boxes C' and C² before reaching the switch and that the car should take the straight track, the switch being in position to deflect the car to the right. As the car approaches the switch-boxes C' and C² the operator closes the switch F', thereby sending a current through the magnet D' and energizing it. As the car passes over the switch-box the active magnet will attract the iron bar R' and, lifting it, will bring the vertical arm of crank H' in contact with the points K', L', M', and N'. This closes the motor-circuit, so that the current passes from the trolley-wire E through e' to field-coil O', thence to O² and out along the wire k. The switches in box C' not having been closed, the current can only pass out through contact K', thence across and in L' and along wire l to brush p'. After traversing the armature in such direction as to cause it to turn in the direction of the arrow marked I it passes out of brush p² and along wire m to contact M' and across to N' and out wire n to the ground G. The current passing in this direction

causes the motor to so turn that it will throw the tongue to the right and leave the straight track open. Let us now suppose that the next car should take the right-hand track. 5 In this case the switch F^2 is closed and magnet D^2 energized. This attracts the bar R^2 in box c^2 and closes the switches H^2 , those at H' being now open, as magnet D' is inactive. The current from the trolley-wire passes 10 through the fields O' and O^2 and along wire k , as before; but as K' is open it must pass out at K^2 , thence across and in M^2 and along wire m . Thus it passes in brush p^2 and traverses the armature P in a direction opposite 15 to the former direction. Passing out at p' and along wire l , it crosses from contact L^2 to N^2 and thence to ground G . The armature is so wound that reversing the direction of the current in it reverses its polarity and 20 causes it to revolve in an opposite direction—that of arrow marked 2. This of course throws the switch to the other side and opens the right-hand track.

By placing the motor in the base of a trolley-post set on the sidewalk it is thus removed 25 from the dampness and the dirt of the street and is more accessible for the purpose of repairs, attendance, &c.

The switch-boxes C may be closed perfectly 30 tight, so that no dirt or surface water may run in, thereby rendering the device more desirable than if the movable parts were exposed in the street.

A further advantage of my device is that 35 it is not necessary for the operator to know the precise location of the switch—a difficult

thing on a dark night. All he has to do is to close the switch F' or F^2 as he approaches the switch and keep it closed until the switch is reached. 40

Having thus described my invention, what I claim, and desire to protect by Letters Patent, is—

1. In a railway-switch-operating mechanism, wherein an electric motor is employed, 45 a switch adapted to be located in the street, said switch comprising a plurality of conductor-terminals, a pivoted member having a depending contact-face adapted to make contact with said terminals, and a member at 50 right angles to said depending member, said last-mentioned member being adapted to be lifted up by a magnetic field carried by the car.

2. A railway-switch-operating mechanism, comprising an electric motor connected with 55 and adapted to operate the switch, suitable current-switches for causing said motor to throw the switch for either track, said current-switches being located in the road-bed so that they shall be passed over by the car, 60 and electromagnets carried by the car so that they shall pass over the current-switches and means whereby the car-operator may energize one of the magnets in such manner as to operate the desired current-switch. 65

In testimony whereof I have affixed my signature in presence of two witnesses.

W. MILTON BROWN.
